UNITED STATES PATENT OFFICE.

LUTHER S. MUNSON, OF WASHINGTON, DISTRICT OF COLUMBIA.

BUILDING BLOCK.

Application filed October 18, 1922. Serial No. 595,317.

To all whom it may concern:

Be it known that I, LUTHER S. MUNSON, a citizen of the United States, residing at Washington, in the District of Columbia, have invented certain new and useful Improvements in Building Blocks, of which the following is a specification.

The present invention relates to building blocks of the type employed in the construction of all species of permanent building structures such as manufacturing plants, office buildings, dwellings, etc., as well as being adaptable for use in the construction of walls, bridges, conduits, etc.

Objects of this invention are to provide building blocks of sufficient miscellany to make their use practical in the construction of buildings of any size as well as allowing for the embellishment or ornamentation of the building; to provide building blocks which complement one another and are interengaged and locked; to provide a bonded wall which is fireproof as well as weather tight and air tight; and to provide blocks which are hollow to facilitate transportation and also reduce the cost of transportation to a minimum, yet permitting the blocks to be reinforced with a filler of plastic or other material wherever desired or found necessary in order to augment the durability of the wall or other structure in which the blocks are embodied.

A co-ordinate object of the invention is to provide blocks which may be axially superimposed, or arranged in staggered relation, in the formation of a wall, with equally effective results, ample provision being made for the insertion of door and window frames, etc., without weakening the wall or detracting from the appearance of the latter.

Numerous other objects of this invention will be apparent from the following description of the present preferred forms of the invention, taken in connection with the accompanying drawings wherein:

Fig. 1 is a fragmentary plan view of a wall embodying blocks constructed in accordance with this invention;

Fig. 2 is a perspective view of the form of block shown in Fig. 1;

Fig. 3 is a fragmentary plan view of a wall constructed in accordance with this invention employing blocks of a different configuration from those shown in Figs. 1 and 2;

Fig. 4 is a perspective view of a block such as that employed in Fig. 3; and

Fig. 5 is a fragmentary elevational view of a wall illustrating use of the blocks, constructed in accordance with this invention, 60 arranged in staggered relation.

In reducing this invention to practice a block A, such as shown in Fig. 2 of the drawings, may be used in the construction of a wall B as shown in Fig. 1 or in the 65 construction of a wall C shown in Fig. 5. Or if desired the blocks may be of the configuration indicated at D, shown in Fig. 4, and embodied in a wall E as illustrated in Fig. 3 of the drawings.

The block A may be of substantially the same size as a standard brick and may also be of the configuration shown in Fig. 2. The block is preferably hollow and equipped with intermediate strengthening 75 walls 6 which extend transversely thereacross. These walls divide the block into a series of compartments 7 which may be hollow, as shown, or filled with a plastic composition or the like whenever desired or found necessary. One side of each block is equipped with a pair of projections 8, one of which is arranged in proximity to each end of the block, while a projection 9 extends from the block between the projections 8. Upon reference to Fig. 1 of the drawings it will be noted that the inner wall of each projection 8 is straight, as indicated at 10, while the opposite wall is inclined as indicated at 11. Each of the projections 9 has the side walls 12 thereof inclined or converged so that the contour of the projection 9 is dovetailed. The projections 8 and 9 may be formed solid or with openings 13.

In assembling the blocks A different methods may be employed and the blocks interfitted in different ways. However, in each instance it is believed to be preferable to have one block A interfitted with two parallelly arranged blocks, as shown in Fig. 1, so as to provide a continuous union of the blocks. The intermediate projection 9 of one block is positioned between the terminal projections 8 of two adjacent blocks and the inclined faces 11 of said adjacent blocks engaged with the inclined faces 12 of the projection 9. This provides spaces between the straight faces 10 of the projections on the parallelly arranged blocks which are adapt-

ed for the reception of a plastic composition 14 capacitating as a bond or key. Also, spaces are provided between the ends of the block bodies which are also filled with a 5 plastic composition, as indicated at 15, thereby bonding the bodies of the blocks together. The spaces between the ends of the block bodies are predetermined, consequently, the artisan in assembling the blocks 10 in a wall can expeditiously determine whether or not the parallelly arranged blocks have been actuated together into the desired contiguity before the plastic composition is deposited between the projections and the 15 block bodies.

Wherever desired or found necessary, a portion only of a block may be used, such as indicated at F in Fig. 1, especially where it is necessary to finish the terminus of a wall. 20 Also, the fragment of a block may be provided with a recess 16 of dovetail or other configuration in which a wooden "buck" 16' or the like may be mounted to which a window or door frame can be anchored.

25 A wall may be made solely from the blocks A or may be used in conjunction with other blocks, such for instance as the blocks G shown in Fig. 5. The blocks G are of a similar design to the blocks A but are of 30 a height in excess of the height of the blocks A to permit staggering of the blocks. For instance, in the construction of a wall, embodying bricks arranged in staggered relation, two tiers of parallelly arranged blocks 35 are used: One tier may employ a bottom or base row of blocks A which has blocks G superimposed thereon as shown in Fig. 5.

The other tier of blocks is composed solely of the blocks G which are interengaged 40 with the blocks A and G in the manner shown in Fig. 5.

The block D has a pair of projections 17 extending laterally from one face thereof adjacent the opposite ends of the body of 45 the block. The projections may be either tubular as shown in Fig. 4, or solid. A central projection 18 is formed in the body of the block D intermediate the projection 17. The projection 18 may likewise be tubular, 50 as shown, or solid and has its inception at the inner face of the wall of the block opposite to that which carries the projections 17. The wall of the block which carries the projection 17 is intersected by the projection 18. The block D may be of any desired 55 size and may be embodied in a wall with symmetrical blocks or with blocks of various configurations which are equipped with projections interfitting with the projections 60 17 and 18. The outer wall of each projection 17 is oblique or inclined, as indicated at 19, while the inner wall thereof is straight, as indicated at 20. The opposite walls 21 of the projection 18 diverge outwardly. Consequently, in assembling the

blocks the oblique faces 19 of the projections 17 may be urged into engagement with the correspondingly formed faces 21 of the projection 18 thereby providing spaces between the straight sides 20 of the projections 18 70 into which a plastic material 22 may be introduced for the purpose of bonding the blocks together. The ends of the blocks receive a filler of plastic composition therebetween. 75

From the above it is apparent that the wall is constructed in the same manner immaterial of whether blocks A, C, D or G are employed.

If desired corner column blocks may be 80 used in order to add to the ornamental appearance of the walls or to bond the ends and side walls together. For instance in order to illustrate this feature of the invention I have in Fig. 3 shown a corner block 14 85 which in the present instance is shown to be rectangular and is equipped with an integral dovetailed projection 22 on each of two faces thereof. Both of these lugs are adapted for engagement in complementary 90 recesses formed in terminal blocks D' which are fragments of the blocks D. It is of course to be understood that when the corner block H is used it must be slidably engaged, 95 in a vertical plane, with the right angled walls of the building. However, I am aware that in some instances such a construction would be impractical and that it would be necessary to laterally engage the corner blocks with the walls. Where this is either 100 desired or found necessary a portion of each projection 22 may be removed and sufficient plastic composition introduced into the dovetailed recesses of the blocks D' to compensate 105 for the portion of each projection 22 which is chipped off. Also, where desired the blocks H may be filled to produce a solid corner column. 110

In use of blocks constructed in accordance with this invention, it is understood that the outer faces of the blocks may be glazed or otherwise ornamented. Moreover, wherever, desired walls composed of the type of block herein shown may be faced by decorative blocks of any standard construction. It is the purpose of the present invention to utilize building blocks which may be manufactured at a relatively low cost, transported with facility and expedition at a minimum cost, and handled by the workmen with convenience. Moreover, the present invention employs blocks which may be embodied in a wall with precision, in order that the tiers of the wall will be rigidly bonded together. It is not necessary in the construction of a wall embodying the blocks of the present invention to require highly skilled artisans in this art, in order to afford effective results, since the horizontal shifting 125 of the blocks after they have been interen- 130

gaged, automatically seats them in proper position and it is necessary only to deposit the plastic composition at the desired places for securing the blocks. It is moreover to be understood that the blocks of this invention may be made from any desired material and may be molded or otherwise formed and made of any dimensions. Also, various other changes may be made within the scope of the claims appended hereto.

What is claimed is:—

1. A building block including a body equipped with an intermediate and terminal projections on one face, said intermediate projection having the opposite sides thereof tapered and said terminal projections having their inner faces straight and their outer faces tapered.
2. A building block including a body equipped with an intermediate and terminal projections on one face, said intermediate projection having the opposite sides thereof tapered, and said terminal projections being spaced from the ends of said body and having their inner faces straight and their outer faces tapered.
3. A wall including blocks equipped with

projections, certain of which have the opposite faces thereof angularly disposed, one face of each of the other projections being angular, said blocks being movable to interengage said angular faces and provide spaces between the opposite faces of the projections for the reception of a locking medium.

4. A wall construction including a body with intermediate and terminal projections on one face, said intermediate projection being of dovetail shape, the inner faces of the terminal projections being straight and the outer faces tapered and spaced from the terminals of said body, the tapered face of each terminal projection impinging against a side of the dovetail projection on an adjacent block, the straight side of each terminal projection being spaced from the corresponding side of a terminal projection on an adjacent block, and a plastic binder disposed, in the space between said straight faces.

In testimony whereof I affix my signature.

LUTHER S. MUNSON.
